UNITED STATES PATENT OFFICE.

EUGENE H. RENFRO, OF OFFERLE, KANSAS.

MAIL BOX.

Application filed September 9, 1926. Serial No. 134,447.

This invention relates to new and useful improvements in rural mail boxes and has for its primary object to provide a box that is equipped with a hinged lid so associated with respect to the box proper that the weight of the box normally maintains the lid in closed position so as to prevent the accidental opening of the same.

A further object of the invention resides in the provision of a box of this character that is associated with a support in such a manner as to permit the box to be raised and lowered, the association of the box with respect to the lid being such that when the lid is opened, the box will be automatically raised so as to facilitate the withdrawal of the mail, and reversely when the box is forced downwardly upon the support, the lid will automatically move in closed position.

A still further object resides in the provision of a box of this character that is extremely simple of construction, inexpensive of manufacture, and one that is well adapted for the purposes intended.

Other objects will become apparent as the nature of the invention is better understood the same comprising the novel form, combination, and arrangement of parts hereinafter more fully described, shown in the accompanying drawing and claimed.

In the accompanying drawing forming part of this application, and in which:

Figure 1 is a side elevation of a box constructed in accordance with the present invention, the lid thereof being shown as closed.

Figure 2 is a view of the opposite side of the box disclosing the same as being raised above its support and the lid open.

Figure 3 is a detail vertical section taken substantially upon the line 3-3 of Figure 1.

Figure 4 is a similar view taken substantially upon the line 4-4 of Figure 2, and

Figure 5 is an inner side perspective of the lid per se.

Now having particular reference to the drawings, 5 designates a supporting post upon the upper end of which is a box supporting plate 6. The box which is designated 7 is of any preferred shape and capacity having a plano-bottom wall 8 and an open front side. The side walls of the box depend slightly below the sides of the bottom wall 8 so as to provide flanges 9-9 at the opposite sides thereof.

At the open front end of the box 7 is a closure lid 10 provided with a suitable operating knob 11. The lid 10 is of the usual slip-type construction having a flange 12 at the side and top edges thereof for engagement over the sides and top of the box when the lid is closed so as to prevent the passage of dirt or moisture into the box. The ends of the flange 12 at opposite sides of the lid 10 extend below the lower edge of the lid for providing fingers 13-13 that engage over the opposite edges of the post carrying supporting base plate 6, after which they are pivoted thereto as at 14-14.

Extending rearwardly from these fingers 13-13 above their pivotal connection with the plate 6 are arms 15-15 formed at their ends with vertically extending lugs 17-17 that are pivoted as at 18-18 to the flanges 9-9 at opposite sides of the box 7.

Pivots secured to the opposite edges of the post plate 6 adjacent the rear ends thereof as at 19-19 are the outer ends of the side arms of a relatively elongated U-shaped bail 20, the horizontal portion of which extends beneath the box 7 and passes through openings in the box flanges 9-9 as more clearly indicated in Figure 4. For limiting the rearward swinging of this bail 20 I provide lateral pins 21-21 at the sides of the plate 6 beyond the pivotal connections between the plate and said bail and against which the side arms of the bail will rest when the box 7 is in lowered position.

It will be obvious that when the lid 10 is swung to open position, the box 7 will be raised as indicated in Figures 2 and 4. After the mail has been removed from the box, the lid is again closed, and the same will be maintained in such a position due to the weight of the box which is exerted upon the arms 15-15 pivotally connected to the box.

The mail box may be and preferably is equipped with any desirable form of pivotal indicating arm 23 at one side thereof.

It will thus be seen that I have provided a highly novel, simple, and efficient form of mail box that is well adapted for all the purposes heretofore mentioned, and even though I have herein shown and described the invention as consisting of certain detail structural elements, it is nevertheless to be understood that some changes may be made therein without affecting the spirit and scope of the appended claim.

Having thus described the invention, what I claim is:—

In a mail box of the character described, a supporting plate, a mail container open 5 at one end, a lid for the open end of the box, a pivotal connection between the lid and the supporting plate, means between the lid and box for causing the raising of

the box when the lid is opened and the closing of the lid when the box is lowered, and means between the rear end of the box and said supporting plate for maintaining the box in horizontal position when raised or lowered.

In testimony whereof I affix my signature.
EUGENE H. RENFRO.
